CARBURETOR

Bernard C. Phillips, Toledo, Ohio, assignor to The
Tillotson Manufacturing Company, Toledo, Ohio,
a corporation of Ohio

Filed Mar. 18, 1963, Ser. No. 74,003

Term of patent 14 years

(Cl. D77—1)

FIGURE 1 is a top plan view of the carburetor embodying my new design;

FIGURE 2 is a side elevational view of the carburetor illustrated in FIGURE 1;

FIGURE 3 is a bottom plan view of the carburetor shown in FIGURE 1;

FIGURE 4 is a side elevational view of the opposite side of the carburetor illustrated in FIGURE 1;

FIGURE 5 is a view of one end of the carburetor, and FIGURE 6 is a view of the other end of the carburetor.

I claim:

The ornamental design for a carburetor, as shown and described.
